ROTARY DRUM DRYING MACHINE

August C. Purpura, Chicago, Ill.

Application February 3, 1945, Serial No. 576,002

7 Claims. (Cl. 34—134)

1

It is common practice to dry laundry by tumbling it in a suitable receptacle while subjecting it to a fluid drying medium, usually heated air. All of the machines for this purpose, of which I am aware, have serious faults which render them inefficient and, generally, not as satisfactory as is desirable.

The object of the present invention is to produce a machine for drying laundry and similar goods, which shall be simple in construction, durable, highly efficient and easy to operate.

The various features of novelty whereby my invention is characterized will hereinafter be pointed out with particularity in the claims; but, for a full understanding of the invention and of its objects and advantages, reference may be had to the following detailed description taken in connection with the accompanying drawings, wherein:

Figure 1 is a perspective view of a machine that embodies the present invention; Fig. 2 is a section, on a larger scale, taken on a central, vertical plane extending from the front of the machine to the rear; Figs. 3 and 4 are sections taken on lines 3—3 and 4—4, respectively, on Fig. 2, Fig. 4 being on a still larger scale; and Fig. 5 is a section on line 5—5 of Fig. 4 on a scale still further enlarged.

Referring to the drawings, 1 represents a casing that is rectangular in shape in vertical and in transverse cross section. The depth of the casing, from front to rear, is progressively reduced from a point a little more than one half of the way up, in a manner to cause the upper part of the front wall 2 to slope rearwardly as the top is approached. In this sloping wall is a round opening 3 through which the work may be introduced and removed. In the casing is a partition 4 that extends rearward, at a slight downward slope, from a point about half way up on the front wall, and then upwardly and rearwardly to the back wall a little below the top of the casing. Thus the casing is divided into upper and lower compartments. In the rear wall of the casing, just above the upper end of the partition, are outlets 5 for the escape of air and vapors. In the bottom of the lower compartment, near the back, is a tank or reservoir 6 to which a drain pipe or spout 7, connected with the lowest point in the upper compartment, leads. A small flue 8 connects the top of the tank or reservoir to outlets 9 in the rear wall of the casing. With this arrangement, liquid water in the upper compartment can flow down into the tank or reservoir

2

and any vapors that are evolved in the latter can escape through outlets 9.

In the upper compartment within the casing is a receptacle for the work to be dried, the same taking the form of a large, round bowl 10 flanged inwardly at what is the top or rim of an ordinary bowl to reduce the effective mouth 11 to about the size of the door opening in the casing. This receptacle lies directly behind the sloping portion of the front wall of the casing, with its axis at right angles to the latter and containing the center of the door opening. When the door 12, cooperating with the opening 3, is opened work can be placed in or be taken out of the receptacle. The receptacle is fastened to one end of a large open ended shaft 14, tubular in form; the shaft being coaxial with the receptacle which has its bottom wall cut away, as indicated at 15, to provide a large opening the center of which is at the axis of the shaft.

Within the receptacle is a long hollow hub or thimble 16, almost as long as the depth of the receptacle and coaxial with shaft 14. The member 16 is preferably cylindrical and it is filled with small holes 17, distributed around the circumference and throughout the length thereof. Furthermore, this member is conveniently thin walled, taking the form of a light shell the open end of which may be slipped over a hub or short projection 18 on a clamping plate 19 between which and a flange 20 on the end of shaft 14 the bottom wall of the receptacle is clamped, as best shown in Fig. 4. The thimble may be held in place on the part 18 by an ordinary bayonet joint 21, as indicated in Fig. 2, whereby it may be removed at will.

In order that the shaft 14 may be firmly supported, I place a second partition 22 in the casing; this partition being roughly in the form of a frusto-conical pan, larger in diameter than the receptacle, surrounding the latter but in spaced relation thereto, and secured at its rim to the walls of the casing. Surrounding the shaft, between and supported by the two partitions, is a heavy bearing sleeve 24 which gives adequate support to the shaft. The partition 22 is perforated, as indicated at 25, throughout the length and circumference of its frusto-conical wall; thereby enabling water in both liquid and vapor form to escape.

In the top of the casing is a trough-like partition 26 that serves as a baffle in the path of fluids leaving the extreme upper part of partition 22 and forcing such fluids to travel downward some distance, and then upwardly, before reach-

ing the outlets 5 in the rear wall of the casing. This causes the liquid to separate from the vapor and flow down into the bottom of the upper compartment, while the vapor rises and escapes through the outlets 5.

There is a bearing sleeve 27 extending through and fast in shaft 14 and clamp member 19. Extending through and being a rotatable fit in this sleeve is a second, smaller, tubular shaft 28 for driving a blower rotor within the thimble which serves as the blower casing. In the arrangement shown, the inner end of the shaft 28 is so modified that it acts as the blower rotor; large sections 29 being partially severed and bent outwardly to form fan blades. Air is drawn in through the outer open ends of the shafts, when the machine is in operation, and reaches the blades through the openings 30 left in the inner shaft in the fashioning of the blades; the blades then driving such air forcibly through the holes in the thimble and radially across the interior of the receptacle. For the purpose of driving the shafts I place on the outer end of the outer shaft a wheel 31 and on the end of the inner shaft 28, that protrudes from the outer end of the outer shaft, a second wheel 32. These wheels may conveniently be driven by separate belts, 34 and 35, which are in turn driven by an electric motor 36 in the lower compartment in the casing.

In order to heat the air before it enters the receptacle I locate an electrically energized heating element 37 within that part of the inner shaft that is surrounded by the thimble. Supporting rods 38 for this element extend through the outer end of shaft 28 to a bracket 39 fixed to the casing. Also located in the space surrounded by the shaft within the thimble is an element 40 of a thermo-responsive temperature controller which is likewise supported from the bracket 39. If desired, the part of shaft 28 beyond the thimble may be lined with asbestos or other suitable heat insulator. In the arrangement shown, this insulating material is in the form of a sleeve 41 loosely entered in the shaft.

It should be noted that what may be termed the side wall of the receptacle is filled with perforations 42 for the escape of fluids, and with ribs 43 for raising the work as the receptacle revolves.

In using the machine, the work is placed in the receptacle and the casing door is closed. The motor is started and the heater is energized. As the receptacle revolves the work is lifted and dropped, resulting in the effective tumbling thereof to present a maximum surface area to the action of the drying medium. The air for drying is drawn in through the open ends of the shafts, is heated and is then driven through the perforations in the thimble in all directions radially of the receptacle, effectively contacting all parts of the work, wherever they may be. When the air reaches a predetermined temperature the controller or regulator acts to shut off or reduce the current that energizes the heater, so that the danger of scorching is avoided. The moisture in the work is quickly vaporized and is progressively driven out through the perforated wall of the receptacle, then passing through the perforated partition and finally escaping from the upper compartment in the form of vapor through outlets 5 or in liquid form through the drain pipe. Because of the constant tumbling of the work and uninterrupted blowing of air against the same, the work dries relatively free from wrinkles or creases.

While I have illustrated and described with par-

ticularity only a single specific form of my invention, I do not desire to be limited to the exact structural details so illustrated and described; but intend to cover all forms and arrangements coming within the definitions of the invention constituting the appended claims.

I claim:

1. In a drying machine, a receptacle for the work, a rotatable, hollow, open ended shaft fixed to and supporting the receptacle for rotary movements, a long cylindrical thimble fixed to the receptacle, within the same and in registration with the said shaft, the thimble being perforated circumferentially and lengthwise, a second hollow shaft extending through and rotatable in the first shaft and extending into the thimble, a blower rotor mounted on the second shaft within the thimble for drawing air through that shaft and discharging it through the perforations in the thimble, means to drive both shafts, a heater positioned in that part of the second shaft that extends into the thimble, and means extending from the heater through the second shaft to the casing beyond the outer end of the latter for supporting the heater.
2. In a drying machine, a receptacle for the work, a rotatable, tubular shaft open at the ends and fixed to and supporting the receptacle for rotary movements, a long cylindrical thimble fixed in the receptacle coaxial with and in open communication with said shaft, the thimble being perforated circumferentially and lengthwise, a second, inner open-ended tubular shaft rotatable in the first shaft and extending into the thimble, the portion of the inner shaft within the thimble having sections partially severed therefrom and bent laterally to produce a blower rotor adapted to draw air through the inner shaft and discharge it through the perforations in the thimble, and means to drive both shafts.

3. A machine such as set forth in claim 2, having, in addition, a heating element positioned within that part of the second shaft that extends into the thimble, a support extending from the heating element through and to the outer end of the inner shaft, and means to secure said support to the casing.

4. In a drying machine, a casing provided with a partition dividing it into upper and lower compartments, a reservoir in the bottom of the casing, a drain for water leading from the bottom of the upper compartment to said reservoir, and there being through the casing wall an outlet for air and vapor from the upper regions of the upper compartment and also from the reservoir, a rotatable perforated receptacle in the upper compartment, a tubular open ended shaft extending through said partition and rotatably supporting the receptacle, means in the receptacle to draw air into the same through said tubular shaft and discharge it laterally across the interior toward the sides of the receptacle, and means to rotate said shaft.

5. In a drying machine, a receptacle for the work, a hollow, open-ended shaft fixed to and supporting the receptacle for rotary movements, a long cylindrical thimble fixed in the receptacle in registration with the shaft, the periphery of the thimble being perforated, a hollow blower rotor in said thimble for drawing air through said shaft and discharging it through said perforated periphery of the thimble, means extending from the blower rotor through and to the outer end of the shaft to rotate said rotor, a heater within the rotor, and means extending

from the heater through the shaft to the casting for supporting the heater.

6. A machine as set forth in claim 5, wherein the means for supporting the rotor is a tubular shaft open at the outer end and fitting rotatably in the shaft that supports the receptacle. 5

7. A machine as set forth in claim 5, wherein the means for rotating the rotor is a tubular shaft open at the outer end and fitting rotatably in the shaft that supports the receptacle, and 10 wherein the rotor constitutes a continuation of the inner shaft.

AUGUST C. PURPURA.
